UNITED STATES PATENT OFFICE.

JAMES M. LEWIS, OF CORAOPOLIS, PENNSYLVANIA, ASSIGNOR TO CONSOLIDATED LAMP AND GLASS COMPANY, OF CORAOPOLIS, PENNSYLVANIA, A CORPORATION OF WEST VIRGINIA.

DESIGN FOR A SHADE.

49,270.

Specification for Design.

Patented June 27, 1916.

Application filed December 28, 1914. Serial No. 879,405. Term of patent 7 years.

To all whom it may concern:

Be it known that I, JAMES M. LEWIS, a citizen of the United States, residing at Coraopolis, in the county of Allegheny and State of Pennsylvania, have invented a new, original, and ornamental Design for Shades, of which the following is a specification, reference being had to the accompanying drawings, forming part thereof, in which—

Figure 1 is a side elevation of a shade embodying the design, and Fig. 2 a plan view thereof.

This invention relates to a new, original and ornamental design for shades for illuminating appliances such as electric, gas and candle lights, chandeliers, table lamps, wall brackets, candelabra, and lighting fixtures generally.

Copies of this patent may be obtained for five cents each, by addressing the "Commissioner of Patents, Washington, D. C."

The present invention therefore as shown by the drawings involves in a unitary structure an elongated candle-like hollow body portion 1, flared outwardly at its upper end as at 2, and surmounted by a relatively enlarged translucent shade 3, thus forming in its entirety a hollow bulbous article of manufacture as and for the purposes indicated.

What I now claim is:

The ornamental design for a shade as shown and described.

In testimony whereof I affix my signature in the presence of two subscribing witnesses.

JAMES M. LEWIS.

Witnesses:

WILLIAM A. SARGEANT,
JACOB F. KIRK.
